HOMER H. JUSTICE AND HUGH J. BENNETT, OF PASADENA, CALIFORNIA.

BUCKET ATTACHMENT.

1,414,285.

Specification of Letters Patent. Patented Apr. 25, 1922.

Application filed January 3, 1921. Serial No. 434,531.

To all whom it may concern:

Be it known that we, HOMER H. JUSTICE and HUGH J. BENNETT, citizens of the United States, residing at Pasadena, in the county of Los Angeles and State of California, have invented new and useful Improvements in Bucket Attachments, of which the following is a specification.

It is the object of this invention to provide an attachment for a bucket or the like adapted to support a paint brush or similar article when the same is not in use. The invention contemplates the provision of such an attachment readily mounted upon a bucket and as readily removed therefrom, and also provides means whereby the attachment may be swung downwardly into inoperative position within the bucket when the latter is being transported, and may be quickly swung upwardly into position for use.

The invention will be readily understood from the following description of the accompanying drawings, in which—

Figure 1 is a perspective view of a bucket having the attachment mounted thereon and swung into position for use.

Fig. 2 is a similar view showing a portion of the bucket and the attachment swung into inoperative position within the bucket.

Fig. 3 is a vertical section through the bucket and through the attachment, showing the latter in its operative position.

Fig. 4 is a detail section on the line 4—4 of Fig. 3.

The attachment may be mounted upon a usual bucket 1 having a rim 2 and provided with a usual handle 3.

The attachment comprises a supporting plate 4, preferably rectangular. This supporting plate may be formed of sheet metal and is provided at three of its sides with a strengthening rib 5 formed by bending the edge of the metal upwardly, as shown at 6, and then reversely bending the same upon itself, as shown at 7, so as to form a strengthening rib extending beyond both faces of the supporting plate. The fourth side of the supporting plate is formed as a straight edge 8, and when the plate is supported upon the bucket this straight edge extends within the bucket while the flanged side edges at the respective ends of the straight edge rest upon the rim of the bucket, as clearly shown in Figs. 1 and 3, so that the

supporting plate is held against rocking movement upon the bucket rim.

The means employed for mounting the supporting plate upon the bucket includes a spring clip 10 reversely bent upon itself 60 and received over the rim of the bucket, with one arm 11 of the clip resting against the exterior surface of the bucket, and the other arm 12 of the clip positioned against the interior surface of the bucket. 65

At the lower end of arm 12 of the spring clip a supporting arm 13 is hinged to the same, as shown at 14, and the end of this supporting arm is angularly disposed, as shown at 15, so as to form a base which is 70 connected to the under side of the supporting plate.

By the arrangement as thus described it will be seen that when the spring clip is mounted upon the bucket that supporting arm 13 may be swung back against the spring clip, as shown in Fig. 3, and when in this position supporting plate 4 extends over the rim of the bucket so that a brush or the like resting upon the supporting plate is so 80 positioned that the drip from the same will return to the bucket.

When the supporting plate is not in use the arm 13 is swung downwardly within the bucket, as shown in Fig. 2, so that the supporting plate is received entirely within the bucket, and in such a position as to not interfere with the ready transportation of the bucket. 85

In order to positively retain a brush or the like upon the supporting plate, the latter may be provided with rivets 20 projecting through the same and terminating in rearwardly inclined prongs projecting beyond the supporting plate. By this construction 95 a brush upon the supporting plate will be held against displacement through engagement with the prongs, even when the supporting plate is tilted downwardly within the bucket. 100

It will be apparent that various changes may be made in the construction as thus described, without departing from the spirit of the invention as claimed.

What is claimed is:

1. The combination with a bucket, of a supporting clip upon the rim thereof, a supporting arm pivoted to said clip, and a supporting plate mounted at its underside upon said arm and having an edge flange resting 110

against the bucket rim when the plate and arm are swung to operative position.

2. The combination with a bucket, of a supporting plate, a spring clip received over 5 the rim of said bucket, an arm hinged to the spring clip at the lower inner end of the latter and carrying the supporting plate, said arm being arranged to swing from position alongside of said spring clip with the

supporting plate resting upon the rim of the 10 bucket to a position within the bucket and with the supporting plate extending substantially vertically downward within the bucket.

In testimony whereof we have signed our 15 names to this specification.

HOMER H. JUSTICE.
HUGH J. BENNETT.
